UNITED STATES PATENT OFFICE.

HERMAN RONNAU, OF EVERGREEN PARK, ILLINOIS, ASSIGNOR OF ONE-HALF TO OTA P. LIGHTFOOT, OF CHICAGO, ILLINOIS.

ROOFING-TILE.

1,023,878.

Specification of Letters Patent.

Patented Apr. 23, 1912.

Application filed June 14, 1909. Serial No. 502,159.

To all whom it may concern:

Be it known that I, HERMAN RONNAU, a citizen of the United States, residing at Evergreen Park, county of Cook, and State 5 of Illinois, have invented new and useful Improvements in Roofing-Tiles, of which the following is a specification.

This invention relates to roofing tiles, and the object of the invention is to provide a 10 roofing tile which may be readily secured in place upon the building without nails, screws or other like fastening.

Another object is to provide means whereby any of the tiles may be removed from the 15 roof without displacing or removing any of the other tiles.

To such ends this invention consists in certain novel features of construction and arrangement, a description of which will 20 be found in the following specification and the essential features of which will be more particularly set forth in the claim.

The invention is illustrated in the drawings furnished herewith in which—

25 Figure 1 is a vertical cross section of a fragment of a roof containing my invention, the line of section being indicated at 1—1 Fig. 2, Fig. 2 is a fragmental side view of the parts seen in Fig. 1, Fig. 3 is a detail 30 vertical cross section illustrating the means for securing the tile in place and Fig. 4 is a perspective view of one of the tiles looking at the lower face thereof.

In these views, 10—10, represent the 35 rafters of an ordinary gable roof and 11—11, a plurality of cleats which are nailed or otherwise secured to the rafters. The cleats run longitudinally of the roof and are suitably spaced apart so as to properly hold 40 and carry the tiles 12, which are to be connected therewith.

As shown in Fig. 4, the tile 12, comprises 45 a plate 13, of suitable size and shape and having a laterally projecting rib 14, formed thereon, which extends across or part way across the under face of the tile. The lower edge of the rib is provided with a bead or projection 15, for locking the tile upon the cleat 11. The tile may be composed of 50 cement, concrete or any other suitable material adapted to protect the interior of the house from the weather and if desired may be coated with some waterproof solution.

The tiles are secured in place by hooking 55 the ribs 14, over the cleats 11, the beads

15, entering grooves or notches 16, formed in the cleats. In the form shown in the drawings the rib 14, is so placed with reference to the top edge of the plate 13, that the plate will extend over three cleats, the 60 upper end of the plate resting upon the cleat located next above the one upon which the rib of the tile is hooked. The result is that each plate overlaps the one below for quite a distance and also overlaps somewhat 65 the second one below, thereby effectually protecting the house from the inclemencies of the weather. It should be noticed that some clearance is left between the upper end of each tile and the downward projection 70 on the tile next above, so that in removing any one of the tiles it may be moved upward to disengage the bead from the groove in the cleat. In laying the tiles, it is desirable to break joint to prevent rain 75 and wind from entering. The apex of the roof is covered by a coping block 17, which may be secured thereto in any suitable manner, preferably by cementing it in place. In order to give the roof a symmetrical appear- 80 ance, the uppermost tiles have their upper ends cut away practically down to the ribs 14, and the coping block is provided with flanges 18, that extend down over the outer faces of the uppermost tiles and give a 85 finished appearance to the roof.

It is evident that the tiles will stay in place by reason of the engagement of the beaded rib with the cleats, and that it will be almost impossible for rain or wind to 90 blow in between the contiguous tiles. Furthermore, in case it is desired to remove a tile, all that is necessary to be done, is to push the tile upward until the bead 15, is disengaged from its seat in the cleat, raise 95 the tile until the rib is free of the cleat and then withdraw the tile. A new one can be readily inserted in its place by merely forcing it in between the tiles adjacent to the space which is to be occupied by the new 100 tile.

I am aware that alterations and modifications of this device are possible without departing from the scope of the invention, and I do not desire to limit myself to the 105 exact form shown and described.

I claim as new and desire to secure by Letters Patent:

In roofing tiles adapted to form a multiple thickness, shingle like, over the entire area 110

covered, a tile having the portion to be overlapped a plane plate adapted to extend over one roof rib, across the intervening space, and partially across the next rib above, 5 and provided with a transverse hooked projection to engage the upper edge of the rib first mentioned while the tile overlaps more than half the length of the similar underlying tile next below; whereby each tile is

held against outward lifting and downward 10 sliding, the arrangement being such that it may be readily pushed upward to disengage the hooked projection.

HERMAN RONNAU.
